SUPERACOUSTIC COMPRESSOR

Filed Nov. 23, 1943

FIG. 3.

FIG. 1.

UNITED STATES PATENT OFFICE

2,435,236

SUPERACOUSTIC COMPRESSOR

Arnold H. Redding, Swarthmore, Pa., assignor to
Westinghouse Electric Corporation, East Pitts-
burgh, Pa., a corporation of Pennsylvania

Application November 23, 1943, Serial No. 511,437

3 Claims. (Cl. 230—120)

1

This invention relates to gas compressors and it has for an object to provide an improved device of the character set forth.

In the design of kinetic machines the practice generally is to avoid superacoustic flow velocities because of the losses associated with compression shock waves, which usually are added to all losses associated with subacoustic flow velocity, thereby causing a general decrease in the efficiency of the apparatus. This is especially true in the case of an expander or nozzle where the desired result is to convert pressure energy into velocity energy. However, a compression shock occurring normal to the path of flow of the medium traveling at superacoustic velocity is a good way of converting the velocity energy into pressure energy, which is the function of a compressor.

It is, accordingly, a further object of the invention to provide an improved compressor in which the medium to be compressed is subjected to a compression shock normal to its path of flow while traveling at superacoustic velocity relative to the moving compressor blades, between which the shock occurs.

By my invention I have provided a compressor, which by a single stage may achieve a compression ratio normally obtained with a plurality of stages in a conventional axial flow compressor.

In general, the moving blades of the present compressor have small camber and sharp inlet and outlet edges. The medium being compressed is supplied to the moving blades by guide vanes at such a direction and velocity relative to the moving blades that the medium is traveling at superacoustic velocity with respect to the inlet edges of the moving blades, thus there is a superacoustic velocity field at the inlet side of the moving blades. The medium traveling at superacoustic velocity is suddenly subjected to a normal compression shock front and reduced to a subacoustic velocity at the throat of the passage between adjacent moving blades. This sudden reduction in velocity provides an immediate pressure increase in the medium at or immediately following the throat region of the blades and the medium, then traveling at subacoustic velocity, gradually undergoes a further velocity-pressure conversion in the remaining portion of the blade passage, which is preferably designed to function as a diffuser.

While the theoretically perfect moving blades of the compressor would have no camber and no thickness, I have shown one blade shape, which is approximately diamond-shaped in section from root to tip, providing sharp inlet and outlet edges,

2

and which provides a throat between adjacent blades substantially parallel to the path of the medium entering the blades. This blade shape also provides a diffuser portion from the throat to the outlet of the blade passages which tends to further effect compression of the medium.

These and other objects are effected by the invention as will be apparent from the following description and claims taken in connection with the accompanying drawing, forming a part of this application, in which:

Fig. 1 is a sectional view of one-half of a compressor made in accordance with the present invention;

Fig. 2 is a fragmentary developed plan view of the guide vane and moving blade, and straightening vane structure of the compressor shown in Fig. 1; and,

Fig. 3 is a vector diagram illustrating the velocity relations of the guide vanes, blades and straightening vanes.

The compressor, indicated generally at 10, comprises an outer tubular casing structure 11 having a central core structure, generally indicated at 12, which defines with the casing 11 an annular flow passage 13 through which the medium to be compressed flows. The left or inlet end 14 of the casing structure together with a rounded nose portion 15 of the central core structure defines an annular inlet to the compressor which is of gradually diminishing flow area. The surfaces of the inlet are smoothly curved to keep turbulence of the medium to be compressed at a minimum.

A plurality of circumferentially-spaced guide vanes 16 extend across the inlet of the passage and are connected at their inner ends to the nose portion 15 and at their outer ends to the casing structure 11, and serve to support the nose portion axially of the compressor.

The guide vanes 16 are preferably of airfoil section to minimize turbulence and are shaped to direct the gaseous medium at the proper angle to the plane of rotation of moving blades 17 of the compressor.

The core structure 12 also includes a drive shaft 18 mounted in suitable bearings (not shown) carried by the casing structure and driven by any suitable means at a speed sufficient to provide a relative velocity between the medium and the inlet edges of the rotor blades 17 which is superacoustic. The drive shaft 18 carries a rotor disc 19 on which the moving blades 17 are fixed.

While the optimum rotor blade would be flat and of no thickness, this of course is not possible. Further, the inlet and outlet edges of the rotor blades should be sharp and have a minimum camber to keep turbulence of the medium as low as possible. The rotor blades 17 shown in the drawing have been found effective and are approximately diamond-shaped in section from root to tip so that the leading edge 21 of each blade forms with the apical portion 22 of the preceding blade a slightly restricted throat in the blade passage in which the compression shock occurs. Referring to Fig. 2, this throat is substantially parallel to the path of flow between the blades 17 and is represented approximately by the area lying between the broken lines 23 connecting the upper and lower ends of the leading edge 21 of a moving blade with the upper and lower ends, respectively, of the apex 22 of the preceding blade. From this throat, the adjacent surfaces of each blade diverge slightly to provide a diffuser passage between pairs of blades.

Rearwardly of the rotor blades, an annular passage 24 serves to direct the medium away from the blades 17 and is defined by an inner ring structure 25 supported from the casing structure 11 by means of straightening vanes 26. One or more rows of these vanes may be provided for straightening the flow of the medium to bring it axially of the compressor.

The vanes 26, in addition to straightening the flow of the medium, also tend to effect a velocity to pressure conversion of the medium to further increase the pressure of the medium.

In Fig. 3, the vector diagram represents the velocity of the medium and compressor blades to illustrate the velocity to pressure conversion occurring when the medium is subjected to a compression shock while traveling at a superacoustic velocity relative to the moving blades 17. The vector 28 represents the velocity of the air entering the guide vanes 18. The medium is turned and accelerated by the guide vanes, resulting in a velocity, represented by the vector 29, on leaving the guide vanes. Thus, the medium on entering the moving blades, the velocity of which is represented by vector 31, has a velocity relative to the moving blades represented by the vector 32, this relative velocity being of superacoustic value. When the compression shock occurs between the moving blades, an immediate velocity to pressure conversion takes place, resulting in a lowered velocity, as represented by the vector 33, and an attendant increase in pressure.

While further compression may occur in the diffuser portion of the blade passage, after the medium has been subjected to shock at the throat region, the vector 33 is assumed to represent also the velocity of the medium leaving and relative to the moving blades. The velocity of the medium with respect to the casing, on leaving the blades 17, is represented by the vector 34, which is the resultant of vectors 33 and 31. As the medium passes between the straightening vanes 26, the medium is turned so that a further velocity to pressure conversion takes place and the medium again flows substantially axially of the compressor, as indicated by the vector 35.

The term "sharp" in the specification, when applied to the edges of the blades or vanes refers to the ratio of the radius of curvature of such edges to a reference dimension of the passage width, for example, the width of the throat area, indicated at 23 in Fig. 2, said ratio preferably

being in the nature of one per cent and in any event not over five per cent.

While the invention has been shown in but one form, it will be obvious to those skilled in the art that it is not so limited, but is susceptible of various changes and modifications without departing from the spirit thereof, and it is desired, therefore, that only such limitations shall be placed thereupon as are specifically set forth in the appended claims.

What is claimed is:

1. A compressor comprising a casing structure, a compressor rotor journaled axially in said casing structure and defining therewith an annular flow passage, blading carried by said rotor and extending across said annular flow passage, guide vanes carried by said casing structure and extending across said flow passage forward of said rotor blades and arranged to direct the gaseous medium to be compressed at a proper angle to said rotor blades, said rotor blades being substantially diamond-shape in section from root to tip and leaving sharp inlet and outlet edges and intermediate apical portions, said blades being arranged so that the inlet edge of each blade together with an apical portion of the adjacent leading blade defines a restricted throat in the passage between the blades, said throat being substantially aligned with the direction of flow of the gaseous medium flowing through the blade passage for effecting a normal compression shock to gaseous medium entering said throat at superacoustic velocity relative to the moving blades and thereby provide an immediate reduction in the velocity of said medium and an immediate increase in the pressure thereof.
2. A compressor comprising a casing structure having an annular air-flow passage, a compressor rotor journaled axially in said casing structure, blading carried by said rotor and extending across said annular flow passage, means extending across said flow passage forward of said rotor blades for directing the gaseous medium, to be compressed, at a proper angle to said rotor blades, said blades having sharp inlet and outlet edges and being so constructed and arranged as to provide a normal compression shock to the gaseous medium entering the blades to provide an immediate reduction in the velocity of said medium relative to said rotor blades and thereby effect an immediate increase in the pressure of said medium.

3. A compressor comprising a casing structure, a compressor rotor journaled axially in said casing structure and defining therewith an annular flow passage, blading carried by said rotor and extending across said annular flow passage, guide vanes carried by said casing structure and extending across said flow passage forward of said rotor blades and arranged to direct the gaseous medium to be compressed at a proper angle to said rotor blades, said rotor blades being substantially diamond-shape in section from root to tip providing sharp inlet and outlet edges and immediate apical portions, said blades being arranged so that the inlet edge of each blade together with an apical portion of the adjacent leading blade defines a restricted throat in the passage between the blades, said throat being substantially aligned with the direction of flow of the gaseous medium flowing through the blade passage for effecting a normal compression shock to gaseous medium entering said throat at a superacoustic velocity relative to the moving blades and thereby provide an immediate reduction in

the velocity of said medium and an immediate increase in the pressure thereof, and straightening vanes carried by said casing and extending across said flow passage rearward of said moving blades for directing the gaseous medium leaving 5 said moving blades substantially axially of the compressor.
